UNITED STATES PATENT OFFICE

149,933

DESIGN FOR A DISPENSING HOLDER FOR BOTTLES OR THE LIKE

Edwin F. Bushman, Aurora, Ill.

Application June 12, 1946, Serial No. 130,649

Term of patent 14 years

(Cl. D53—26)

To all whom it may concern:

Be it known that I, Edwin F. Bushman, a citizen of the United States, residing at Aurora, in the county of Kane and State of Illinois, have invented a new, original, and ornamental Design for a Dispensing Holder for Bottles or the like, of which the following is a specification, reference being had to the accompanying drawing, forming a part thereof.

In the said drawing—

Figure 1 is a perspective view of a dispensing holder for bottles or the like showing my new design; and

I claim:

The ornamental design for a dispensing holder for bottles or the like, as shown.

EDWIN F. BUSHMAN.
